TIMER AND DISTRIBUTING DEVICE.

1,080,788.

Specification of Letters Patent.

Patented Dec. 9, 1913.

Application filed May 17, 1912. Serial No. 697,886.

To all whom it may concern:

Be it known that I, JAMES M. SMITH, a citizen of the United States, residing at Philadelphia, in the county of Philadelphia and State of Pennsylvania, have invented certain new and useful Improvements in Timers and Distributing Devices; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in timing and distributing mechanisms for the ignition systems of internal combustion engines; and, the present invention has reference, more particularly, to a novel construction of automatic timing and distributing mechanism for controlling an electric current, to intermittently make and break the circuit thereof, and successively connect the sparking-terminals of a plurality of engine-cylinders with the source of generation of said electric current, so as to successively ignite or explode the charges of gas within the cylinders of the engine.

The present invention has for its principal object to provide a novel, simple, and effective mechanism of the character above set forth, adapted to be geared in connection with the main shaft of an explosive engine in such a manner, that its parts operate in a properly timed relation to the respective pistons of the engine cylinders.

A further object of the invention is to provide a novel construction of contact-mounting for the make and break device, which is easily and effectively operated to advance or retard the contact-closing periods of the make and break device, and to advance or retard the time of production of the sparks within the respective engine-cylinders, such novel contact-mounting being combined with a make and break device which will only operate when the main shaft of the engine turns or rotates in the proper or normal direction.

Other objects of this invention not at this time more particularly enumerated, will be clearly evident from the following detailed description of the said invention.

With the various objects of the present invention in view, the said invention consists, primarily, in the novel electric current-timing and distributing mechanism herein-after set forth; and, the invention consists, furthermore, in the novel arrangements and combinations of the various devices and the parts thereof, as well as in the details of the construction of the same, all of which will be more fully described in the following specification, and then finally embodied in the clauses of the claim which are appended to and which form an essential part of said specification.

The invention is clearly illustrated in the accompanying drawings, in which:—

Figure 1 is a diagrammatic representation of an ignition system, illustrating the proper electrical and mechanical connections of the same with an internal combustion engine, and including a novel timing and distributing mechanism, (illustrated in side elevation), made according to and embodying the principles of the present invention. Fig. 2 is an interior plan view of the internal make and break mechanism; Fig. 3 is a similar view illustrating the normal operation of said make and break mechanism; and Fig. 4 is another similar view, showing the manner in which the said make and break mechanism is prevented from closing the circuit, when the main shaft of the engine turns or rotates in the wrong direction. Fig. 5 is a longitudinal vertical section, taken on line 5—5 in said Fig. 2, looking in the direction of the arrow *x*, the additional distributing mechanism being also shown. Fig. 6 is a detail transverse section, taken on line 6—6 in said Fig. 5, said view illustrating more particularly the distributing mechanism, and Fig. 7 is a detail vertical section, taken on line 7—7 in said Fig. 2, looking in the direction of the arrow *y*.

Similar characters of reference are employed in all of the above described views, to indicate corresponding parts.

Referring now to the said drawings, the reference-character 1 indicates an internal combustion engine, 2 indicates its main shaft, and 3 indicates the sparking terminals or plugs with which its respective cylinders are provided. The reference-character 4 indicates a battery, or other source of electrical energy for supplying the current of

70

75

80

85

95

100

105

the ignition system, and 5 is the usual transformer or induction coil for use in said ignition system.

The reference-character 6 indicates a casing which is adapted to contain and support the novel timing and distributing mechanism. Preferably integrally connected with said casing 6, and being centrally disposed and extending outwardly from the back 7 thereof, is a tubular hub 8 which is provided with a reduced extension 9, adapted to receive a yoke-member or collar 10. Said yoke-member or collar 10 is provided with a support with which connection with a suitable part of the engine-frame may be made, for the purpose of supporting said casing 6 in its proper connection therewith. Journaled in said tubular hub 8, so as to rotate therein as in a bearing, is a spindle 12, said spindle being provided upon its outer end with an enlarged portion or head 13, the latter forming a shoulder which abuts against the outer end of the said reduced extension 9, and thereby prevents any longitudinal movement of the said spindle 12 in an inward direction. The outer end of said spindle 12 is provided with a receiving socket or opening 14, adapted to receive one end of a counter-shaft 15, which is geared in driven connection, by means of the respective gear-members 16 and 16' with said main shaft 2 of the internal combustion engine 1, said counter-shaft 15 being secured in its connection with the said spindle 12 by means of a set-screw 17, or any other desirable form of fastening or coupling means. The inner end of said spindle 12 is provided with a reduced extension 18, which passes through a suitable opening 19 in the back 7 of said casing 6 and penetrates into the interior of said casing. Journaled upon said reduced extension 18, so as to turn freely thereon, is a movable plate or base 20, and suitably secured upon said plate or base 20 is a ring member 21, which registers with the marginal circumference of said plate or base 20. Said ring-member 21 is insulated from electrical contact with the said plate or base 20, by means of an interposed insulating disk or sheet 22, and the fastening screws 23, by means of which said ring-member is secured to said plate or base, are also insulated by means of flanged sleeves 24. Secured upon said ring-member 21 are a plurality of suitably disposed contact-posts 25. Connected with the side walls of said casing 6, but insulated from electrical contact therewith by means of a flange, insulated from electrical contact therewith by means of a flanged insulator-sleeve 26, is an outwardly projecting binding-post 27, to the inner end of which is secured a spring-leaf brush or member 28 which is adapted to contact with any one of the said contact-posts

25, whereby an electrical current, to be subsequently described, passes into said ring-member 21 and the several contact-posts 25 mounted thereon. Connected with said reduced extension 18 of said spindle 12, so as to be rotated thereby, is a disk 29 suitably provided with a hub-portion 30 for engaging said reduced extension 18. Mounted upon said rotating-disk 29 is a post 31 adapted to support an adjustable contact-screw 32, said screw being provided at its free end with a non-corroding contact-point 33. The said rotating disk 29 carries a supporting plate 34, which is insulated from electrical contact with said rotating disk 29 by means of an intervening sheet 35 of a suitable insulating material. Said supporting plate 34 is held in this secured position by means of screws 36 which are also insulated from electrical contact with said supporting-plate by means of suitable insulating sleeves 37. Said supporting-plate 34 is furthermore provided with a suitably disposed cut-away portion or opening 38, by means of which the said plate is permitted to straddle the hub-portion 30 and said post 31, and in such a manner so as to avoid electrical contact therewith.

The reference-character 39 indicates a fulcrum-post, said post being provided with a screw-threaded shank 40 adapted to be screwed into a suitably screw-threaded opening, prepared for its reception, in said supporting-plate 34. The free end of said fulcrum-post is provided with a pivot-stud 41 upon which is pivotally mounted a supporting block 42 of a make and break device. Suitably secured upon the said supporting block is an outwardly extending bracket or arm 43, and suitably connected therewith is a spring-plate 44, said spring-plate paralleling the said bracket or arm 43 and being slightly offset therefrom, so as to give room for the exercise of its spring-like function or yieldableness. The end of the said bracket or arm 43 is doubled upon itself, so as to form a retaining finger 45, which serves to limit the outward movement or spring of said spring-plate 44, and suitably connected with the said spring-plate, in a suitable location, preferably adjacent to its free end, is a non-corroding contact-point 46. Secured upon the opposite side of said supporting block 42, to that upon which said bracket or arm 43 is attached, is an outwardly extending lever or arm 50, which is provided at its free end with a pair of horizontally disposed and perforated ears or bearing-lugs 51 adapted to support a vertically disposed pintle or pin 52. Pivotaly mounted upon said pintle or pin 52 is a pawl-like member 53 which is provided with an outwardly projecting cam-like nosing 54, said pawl or member 53 being also formed with suitable shoulders 55 upon its upper 120

and lower sides which, in their engagement with the edges of said perforated ears or bearing-lugs 51 prevent the said pawl or member 53 from oscillating or yielding in one direction. Connected with said pawl or member 53 is a perforated tail or lug 56 adapted to receive one end of a coiled spring 57, the other end of said spring being secured to an anchor-post 58 formed upon said base-piece 48. The said coil-spring 57 serves the double purpose of maintaining in and returning to normal position both said pawl or member 53 and said lever or arm 50, as well as the bracket or arm 43 and said spring-plate 44. Connected with said lever or arm 50 is a right angled extension forming a stop-arm 47, projecting from the fixed end of said lever or arm 50 and extending across the end-surface of said supporting block 42. Secured upon said supporting-plate 34 is the base-piece 48 of an upwardly projecting stop-portion 49, which is adapted to be engaged by the said stop-arm 47 to limit the pivotal movement of said lever or arm 50; bracket or arm 43, and said spring-plate 44, in one direction, whereby their normal position is located. Suitably connected with the outer end of said casing 6 is a cylindrical casing 59, which is provided, with a cover-plate 60, both of said parts being made of some suitable insulating or non-conducting material. The said cover-plate 60 is provided with a centrally disposed perforation or opening 61 in which is arranged a tubular member or sleeve 62, provided with an annular flange 63 bearing upon the inner surface of said cover-plate 60. Said sleeve 62 is provided at its outer end with an externally screw-threaded part 64 and an internally enlarged portion or opening 65. A chambered or hollow nut-shaped body 66 is screwed upon said externally screw-threaded post 64, against a screw-threaded washer 67 also arranged upon said externally screw-threaded part 64, so as to bear against the outer surface of said cover-plate 60. Said nut-shaped body 66 is provided with an outwardly extending portion 68, from the extreme end of which projects a reduced screw-threaded shank 69 adapted to receive a nut-piece 70, to which may be attached an electrical conductor or wire. Arranged within the internally enlarged portion or opening 65 of said sleeve 62 is the head 71 of a contact-plug or brush 72, a coiled spring 73 being arranged back of said head to press said plug or brush outwardly, and to thereby compel the same to make electrical contact with certain parts of a current distributing mechanism. Connected with the free end of said reduced extension 18 of the spindle 12, by means of a transverse pin 74, or any other suitable fastening means, is a hub-member 75, the same being made of some suitable insulating or non-conducting material. The outer end of said hub-member is provided with a recess or socket adapted to receive the disk-portion 76 of a metallic contact-arm or brush 77, the said disk-portion being secured in any suitable manner to said hub-member, so as to turn or rotate therewith. Secured upon the inner side of said casing 59 are a plurality of suitably disposed contact-points 78, which are provided with screw-threaded shanks 79 which project through and outwardly from the said casing 69, and provide, in connection with nut-members 80, suitable binding-posts to which are secured the respective electrical conductors or wires 81 which connect said distributing mechanism with the several sparking-terminals or plugs 3 connected with the cylinders of the engine 1. Said contact-arm or brush 77 when rotating, successively contacts with the respective contact-points 78 to successively deliver the electrical current for producing the ignition-spark. The previous-mentioned plug or brush 72 is adapted to make constant contact with said contact-arm or brush 77. The primary electrical circuit is run as follows: The battery 4 is connected with the primary winding of the transformer or induction coil 5, the electrical conductor or wire 82 connecting the primary winding of said induction coil 5 with the binding-post 27, whereupon the primary current passes into said ring-member 21 and its contact-posts 25, through the spring-leaf brush or member 28. The spindle 12 being rotated in proper time and speed-relation by means of the main shaft 2 of the engine, the same causes a rotation of the disk 29 and the supporting-plate 34 carried thereby, in the direction of the arrow *a* in Fig. 2. This rotation carries around the make and break mechanism, and thereby brings into successive contact with said contact-posts 25, the cam-like nosing 54 of said pawl or member 53. When so engaged, any pivotal movement of said pawl or member 53 upon its pintle or pin 52 is resisted, since the shoulders 55 thereof are caused to press against the edges of the perforated ears 51 of the lever of arm 50. Consequently, the lever or arm itself is pushed forward or oscillated, so as to turn the said supporting block 42, and thereby carries said bracket-arm 43 and its spring-plate 44 forward, so that the contact-point 46 of the latter is brought into contact with the contact-point 33 of the contact-screw 32, the said spring-plate 44 yielding to the pressure of said contacting points and thereby assuring a positive contact. Such contact having been made, the primary electrical current is bridged through the said make and break mechanism, and thereupon flows into said rotating disk 29, and through the spindles, shafts, etc., into

70

75

85

90

95

100

110

120

125

130

the ground formed by the engine-frame, thence passing through the binding post 83 and the return-wire 84 back to the battery 4, whereby the primary circuit is completed. 5 Upon the making and breaking of the primary circuit the secondary winding of the transformer or induction coil 5 is excited, thereby inducing a secondary electrical current, which is delivered from said transformer coil to the distributing mechanism by the wire or electrical conductor 85, and is thereupon distributed by said distributing mechanism to the sparking-terminals or plugs 3, as above described, and in a manner clearly to be understood by those skilled in the art to which this invention appertains. As the make and break mechanism passes, during its rotation, the several contact-posts 25, it makes contact with the same, thus producing an intermittent making and breaking of the primary circuit, and a consequent intermittent generation of the secondary current, which is properly distributed to the sparking terminals or plugs 25 in accordance with the needs of the engine. When it is desired to advance or retard the time of closing the primary circuit and the consequent generation of the secondary current, the same is accomplished in a very simple and effective manner. To this end, the said plate or base 20 is provided with an outwardly extending stud 86, provided at its free end with an eyelet or ring 87, to which is secured the system of operating levers 88. The back 7 of the casing 6 is provided with an elongated slot or opening 89, through which said stud 86 passes, and which permits the proper movement of the same. By a proper operation of the said levers 87, a pull or push is communicated to said stud 86, which partially rotates or oscillates said plate or base 20 and said ring-member 21, thereby shifting the position of said contact-posts 25 with reference to the rotating make and break-mechanism, and as will be clearly evident, either advancing or retarding the time of the spark-delivery in accordance with the direction of the movement of said contact-posts. 50 If it happens that the main shaft 2 of the engine is rotated, by reason of any cause, in a direction opposite to its normal and operative direction of rotation, the same cam-like nosing 54 of said pawl or member 53 connected with said lever or arm 50 of the make and break mechanism, is so engaged by said contact-posts 25, that the same will yield to the same and will ride over said contact-posts 25 without oscillating said lever-arm 50, as is illustrated in Fig. 4 of the drawings; hence, no closing of the respective contact points 46 and 33 is produced, and the primary circuit remains unbroken. 65 I am aware that changes may be made

in the general arrangements and combinations of the various devices and parts, as well as in the details of the construction of the said parts, without departing from the scope of the present invention, as set forth 70 in the foregoing specification and as defined in the clauses of the claims which are appended thereto. Hence, I do not limit my invention to the exact arrangements and combinations of the various devices and parts as herein described, nor do I confine myself to the exact details of the construction of the said parts, and as illustrated in the accompanying drawings. 75

I claim:—

1. In a device of the class described, a casing, a plate mounted within said casing so as to be capable of rotary oscillation, a ring-member mounted on said plate but insulated therefrom, a plurality of contact-posts 85 mounted on said ring-member, means for connecting said ring-member and said contact-posts in an electrical circuit, a movable contact-device, and a contact means stationary with relation to said movable contact-device, said contact means being connected in said electrical circuit, means for rotating said movable contact-device and said stationary contact means, whereby the former successively engages said contact-posts so as to be moved into circuit-closing contact with said stationary contact means, and means for oscillating said plate and ring-member to shift the position of said contact-posts to advance or retard the operation of said movable contact device. 90 95 100

2. In a device of the kind described, a plurality of contact-posts connected in an electrical circuit, a rotating disk, a stationary contact-device carried by said rotating disk, 105 rotating-disk and stationary contact device being included in said electrical circuit, a supporting plate connected with said rotating disk, but insulated from said rotating disk and said stationary contact-device, a movable contact device pivotally supported upon said supporting plate, means connected with said movable contact-device adapted to successively engage said contact-posts when said rotating disk is rotated in a proper 110 direction, to move said removable contact-device into circuit-closing engagement with said stationary contact-device, but yieldable to said contact-posts without moving said movable contact-device when said rotating 115 disk is rotated in an opposite direction. 120

3. In a device of the kind described, a plurality of contact-posts connected in an electrical circuit, a rotating disk, a stationary contact-device carried by said rotating disk, 125 said rotating-disk and stationary contact device being included in said electrical circuit, a supporting plate connected with said rotating disk, but insulated from said rotating disk and said stationary contact-device, a 130

movable contact device pivotally supported upon said supporting plate, means connected with said movable contact-device adapted to successively engage said contact-posts when 5 said rotating disk is rotated in a proper direction, to move said movable contact-device into circuit-closing engagement with said stationary contact device, but yieldable to said contact posts without moving said movable contact-device when said rotating disk is rotated 10 in an opposite direction, and means for shifting the position of said contact-posts to advance or retard the circuit-closing movement of said movable contact-device.

4. In a device of the kind described, a plate, a ring-member carried by said plate, but electrically insulated therefrom, a plurality of contact-posts supported upon said ring-member, means for connecting said ring-member and contact-posts in an electrical circuit, a rotating-disk, a post provided with an adjustable contact-screw carried by said rotating disk, said rotating disk, post and contact-screw being included in 20 said electrical circuit, a supporting plate connected with said rotating disk, but electrically insulated from said rotating disk, post and contact-screw, a movable contact-device pivotally supported upon said supporting 25 plate, means connected with said movable contact-device adapted to successively engage said contact-posts when said rotating disk is rotated in a proper direction to move said movable contact-device into circuit closing 30 relation to said contact-posts and said contact-screw, but yieldable to said contact-posts without moving said movable contact device, when said rotating-disk is rotated in an opposite direction, and means for oscillating said plate, ring-member and contact- 35 posts to shift the position of the latter so as to advance or retard the circuit-closing or bridging movement of said movable contact-device.

5. In a device of the kind described, a casing, a plate movably mounted within said casing, a stud connected with said plate and projecting through an opening with which said casing is provided, levers connected 50 with said stud for shifting said plate, a ring-member carried by said plate but electrically insulated therefrom, a plurality of contact-posts supported upon said ring-member, means for connecting said ring-member and contact-posts in an electrical circuit, a spindle journaled in said casing, a rotating disk connected with and operated by said spindle, a contact-receiving means connected with said rotating disk and included in said electrical circuit, a supporting plate connected 55 with said rotating disk but electrically insulated from said rotating disk and said contact-receiving means carried thereby, a movable contact-device pivotally supported upon 60 said supporting plate, and means connected 65

with said movable contact-device adapted to successively engage said contact-posts to move said movable contact-device into circuit-closing and bridging contact with said contact-posts and said contact-receiving means when said rotating disk is rotated in a proper direction, but yieldable to said contact-posts without moving said movable contact-device when said rotating disk is rotated in an opposite or wrong direction. 70

6. In a device of the kind described, a casing, a plate movably mounted within said casing, a stud connected with said plate and projecting through an opening with which said casing is provided, levers connected with said stud for shifting said plate, a ring-member carried by said plate but electrically insulated therefrom, a plurality of contact-posts supported upon said ring-member, means for connecting said ring-member and contact-posts in an electrical circuit, a spindle journaled in said casing, a rotating disk connected with and operated by said spindle, a contact-receiving means connected with said rotating disk and included in said electrical circuit, a supporting plate connected with said rotating disk but electrically insulated from said rotating disk and said contact-receiving means carried thereby, a movable contact-device pivotally supported upon said supporting plate, means connected with said movable contact-device adapted to successively engage said contact-posts to move said movable contact-device into circuit-closing and 80 bridging contact with said contact-posts and said contact-receiving means when said rotating disk is rotated in a proper direction, but yieldable to said contact-posts without moving said movable contact-device 85 when said rotating disk is rotated in an opposite or wrong direction, and means for distributing a secondary electrical current 90 operated by said spindle. 95

7. In a device of the kind described, a casing, a plate movably mounted within said casing, a stud connected with said plate and projecting through an opening with which said casing is provided, levers connected with said stud for shifting said plate, a ring-member carried by said plate but electrically insulated therefrom, a plurality of contact-posts supported upon said ring-member, means for connecting said ring-member and contact-posts in an electrical circuit, a spindle journaled in said casing, a rotating disk connected with and operated by said spindle, a contact-receiving means connected with said rotating disk and included in said electrical circuit, a supporting plate connected with said rotating disk but electrically insulated from said rotating disk and said contact-receiving means carried thereby, a movable contact-device pivotally supported upon 100 said supporting plate, and means connected 105 with said movable contact-device adapted to successively engage said contact-posts to move said movable contact-device into circuit-closing and bridging contact with said contact-posts and said contact-receiving means when said rotating disk is rotated in a proper direction, but yieldable to said contact-posts without moving said movable contact-device 110 when said rotating disk is rotated in an opposite or wrong direction, and means for distributing a secondary electrical current 115 operated by said spindle. 120

125

130

plate, means connected with said movable contact-device adapted to successively engage said contact-posts to move said movable contact-device into circuit-closing and bridging contact with said contact-posts and said contact-receiving means, when said rotating disk is rotated in a proper direction, but yieldable to said contact-posts without moving said movable contact-device when said rotating disk is rotated in an opposite or wrong direction, and means for distributing a secondary electrical current comprising a plurality of contact-points, a rotating contact-arm connected with but insulated electrically from said spindle, and means for connecting said rotating contact-arm in the circuit of said electrical current.

8. In a device of the kind described, a casing, a plate mounted within said casing so as to be capable of rotary oscillation, a ring-

member carried by said plate but insulated therefrom, a plurality of contact-posts on said ring-member, means for connecting said ring-member and contact-posts in an electrical circuit, a revolving make and break circuit-closing device adapted to successively engage said contact-posts, and means for shifting said plate and ring-member and its contact-posts so as to be operated by contact therewith, so as to advance or retard the time-relation of the engagement of said circuit-closing device with said contact-posts.

In testimony, that I claim the invention set forth above I have hereunto set my hand this sixth day of April 1912.

JAMES M. SMITH.
